UNITED STATES PATENT OFFICE.

GEORGE H. BLETTNER, OF CHICAGO, ILLINOIS.

CYLINDER-GRINDING TOOL.

Application filed September 2, 1922. Serial No. 585,880.

To all whom it may concern:

Be it known that I, GEORGE H. BLETTNER, a citizen of the United States, and a resident of the city of Chicago, in the county of Cook and State of Illinois, have invented a certain new and useful Cylinder-Grinding Tool; and I do hereby declare that the following is a full, clear, and exact description of the same, reference being had to the accompanying drawings, and to the numerals of reference marked thereon, which form a part of this specification.

The refinishing of the interior surfaces of engine cylinders has heretofore been an expensive matter, calling for a large shop with elaborate equipment.

It is the object of this invention to provide a means for grinding the interior of engine cylinders to a true cylindrical surface without the need of any elaborate or expensive equipment and without the need of any careful placing of the cylinder upon the machine.

It is a further object of this invention to provide a tool which shall automatically center itself within the cylinder to be ground and shall produce a true cylindrical surface.

It is a further object of this invention to provide an improved means for securing the abrasive substance to the working surface of the tool.

It is a further object of this invention to provide means for producing a uniform distribution of lubricant over the surface being ground.

It is a further object of this invention to provide a resilient means for pressing the abrading tool against the surface of the cylinder.

It is a further object of this invention to provide such connections between the resilient means and the several abrading tools that the proper pressure will be applied to each tool.

It is a further object of this invention to provide a grinding means for cylinders which shall not contact with the inner surface of the cylinder at the bottom of scored places but shall confine its cutting action to the portions of the walls above such scored places.

Other and further important objects of this invention will be apparent from the disclosures in the drawings and specification.

The invention (in a preferred form) is

illustrated in the drawings and hereinafter more fully described.

On the drawings:

Figure 1 is a top plan view, and Figure 2 is a side elevation of the tool.

Figure 3 is a section upon the line 3—3 of Figure 2.

Figure 4 is a section upon the broken line 4—4 of Figure 1.

Figure 5 is a bottom plan view of the lower end of the tool.

As shown on the drawings:

A driving shaft 10 is connected to the driven shaft 11 of the tool by two joints 12 to enable the shaft 11 to be rotated by the shaft 10 and yet to be freely displaced laterally in any direction. Mounted upon the shaft 11 is a carrier 13, the upper part of which as shown at 14 is enlarged to constitute a spring barrel. A flat spiral spring 15 is coiled within this barrel, one end of it being secured to the barrel as shown at 16 and the other end of it being secured to the shaft 11 as shown at 17 in Figure 3. A cover 18 for the barrel 14 is pinned to the shaft 11 as shown at 19. Along one part of its edge, the cover 18 is of smaller radius to provide a rabbet 20 having shoulders at its ends to accommodate a pin 21 which extends through the rabbet into a plate 22 suitably mounted upon the shaft 11 between the cover 18 and the barrel 14. One portion of the edge of the plate 22 is provided with teeth 23 which act as a worm wheel meshing with the screw 24 which is mounted in bearings 25 supported in a bracket 26 secured to the side of the barrel 14. At one end the screw 24 is provided with a slot 27 for the reception of a screw driver or similar tool.

The carrier 13 has three pairs of lugs 30 arranged in three radial directions, one pair in each direction, to accommodate three shafts 31 parallel to the shaft 11. Each shaft 31 protrudes through its pair of lugs 30 and engages the arms of a U-shaped carrier 32. Each of these carriers has a pair of horizontal arms engaging the shafts just described and a vertical connecting piece 33. Secured to the vertical portion 33 by means of dove-tailed joints 34 is a strip of abrasive material 35. The abrasive material may be of any desired kind, but I prefer to prepare it by introducing carborundum into fused lead and casting the mixture in moulds of the required form. The cutting face of this

strip of abrasive material is crossed by oblique slots 36 as shown in Figure 2. Extending inward from each of the vertical parts 33 of the arms 32, is a web 37 and wound around each of the shafts 31 is a spring 38, one end of which is anchored in one of the lugs 30 and the other end of which bears against the corresponding web 37. The pressure of these springs tends to cause the arms 32 to move about the shaft 31 in such a direction that the strips 35 move counterclockwise as seen in Figure 1, or clockwise as seen in Figure 5. The shaft 11 where it extends below the carrier 13 has pinned to it a triangular cam piece 40. In one extreme position of this triangular cam piece, the action of the spring 15, which tends to move the cam 40 counterclockwise as seen in Fig. 5, presses the sides of the cam 40 against the sides of the arms 32 close to the pivoted ends of these arms so that the thickness of the arm where it surrounds the pin 31 acts as a stop to limit the movement of the cam 40 in this direction. This extreme position is illustrated in full lines in Figure 5. In the opposite extreme position the straight portions of the arms 32 come against the straight sides of the cam piece 40 as illustrated in dotted lines in Figure 5. The action of the springs 38 keeps the arms 32 against the sides of the cam 40 as it moves toward dotted line position. When the cam arrives at this position the hubs of the arms 32 again act to afford a stop, preventing further movement of the cam 40 clockwise as seen in Figure 5. For convenience in manipulating the tool a pair of recesses to receive the ends of a spanner wrench are provided in the cover 18 as shown at 42, and a similar pair of holes to receive the ends of a spanner wrench are provided in the barrel 14, one of these being shown at 43.

In referring to Figure 5, it will be noted that the maximum relative movement between the shaft 11 and the carrier 13 is defined by the distance between the full line position of the cam 40 and the dotted line position thereof. The tension of the spring 15 is effective between the limits defined by this distance for maintaining the sides of the cam 40 against the sides of the arms 32 in an anti-clockwise direction as viewed in Figure 5. The relative rotation of the shaft 11 to the carrier 13 between the above-mentioned limits is however governed by the range of movement of the pin 21 along the rabbet 20. It is possible to adjust the disks 22 to vary the arcuate travel of the pin 21 and hence the relative movement between the shaft 11 and the carrier 13. Thus the outward travel of the arms 32 may be controlled for any size cylinder between the limits of the maximum relative movement of the shaft 11 and carrier 13.

In the use of the device, the disk 22 may be first adjusted to regulate the device for the proper sized completed cylinder, a spanner wrench may then be applied to the holes 42 for moving the cover 18, and a second spanner wrench to the holes 43 for moving the barrel 14. These two are then moved in opposite directions so that the shaft 11 is rotated by the cover plate 18 relative to the barrel 14 and causes the spring 15 to wind up. This motion also causes the cam 40 to move clockwise in Figure 5 so that the edges of the cam tend to depart from the arms 32, but the springs 38 acting against the webs 37 cause the arms 32 to follow the cam in its movement towards the dotted position.

By comparing the full line position of the arms 32 with the dotted line position of them in Figure 5 it will be seen that the abrading surfaces 35 are nearer the center in the dotted line position than in the full line position. Consequently the movement of the two spanner wrenches just described will cause the effective diameter of the tool to be less so that the tool may be introduced into an engine cylinder. When the tool has thus been introduced, the spanner wrenches are released and the spring 15 moves the shaft 11 counterclockwise as seen in Figure 5 so that the edges of the cam 40 press against the arms 32 and move them from the dotted line position towards the full line position. This causes the abrasive members 35 to spread out and contact with the walls of the cylinder.

It will be observed that each of the abrasive members 35 moves out the same distance, being all moved by the movement of the one shaft 11. The result is that the abrasive members 35 press equally against three lines of contact with the cylinder and so move the tool until the center of the shaft 11 corresponds to the center of the cylinder as determined from these three lines of contact.

Power is then applied to the shaft 10 to rotate the shaft 11 and cause the tool to rotate within the cylinder.

As long as the cylinder is truly round, and the shaft 11 is at its center, this pressure will be equal at all of the members 35. In using the tool upon a worn cylinder, in which the contour is usually irregular, the pressure of the three members 35 brings the shaft 11 to the center of the circle determined by the three lines with which the three members 35 contact. As the tool rotates, one of these members will reach a place where the cylinder is of somewhat larger radius. The pressure of this member against that side of the cylinder will therefore diminish, but the action of the spring 15 in maintaining the cam 40 against the arms 32 tends to equalize the pressure on all

three of the members 35. There will be a tendency to move the member which has found a side of larger radius toward that side. As far as this tendency is represented by an increase in the radial outward movement, it is shared by all three members 35, for they are pressed out equally by the action of the spring 15 and the torque of the shaft 11 acting through the cam 40. There is, however, some tendency for the tool to move sidewise toward the side of the cylinder having a larger radius, and this tendency has a part in equalizing the pressure when the same has been rendered unequal by an irregularity in the shape of the cylinder.

The inertia of the tool as a whole is considerable, for the tool is fairly heavy, and the changes in pressure just discussed are small. Moreover, the time during which any one member 35 tends to move toward any one side of the cylinder is brief. The result is that the abrasive action of the tool does not reach the bottom of a low spot in the cylinder, or, at most, touches it very lightly, until the cylinder as a whole has been enlarged sufficiently so that the new (correct) cylindrical surface reaches to the bottom of the low spot.

If the cylinder possesses a side where the radius is smaller than for the cylinder as a whole, the reverse action takes place. When an abrasive member 35 reaches such a spot, the pressure of the cylinder wall against this member increases and tends to move the arms 32 inward. This tendency is resisted by the pressure of the cam 40 against the arm which has behind it the driving torque of the shaft 11, and this pressure is combined with the action of the spring 15, which holds the inner ends of the arms in close contact with the sides of the cam. It is therefore difficult for the cylinder wall to press the arms 35 inward. Consequently, when an abrasive member 35 meets a high spot in the cylinder wall, the pressure is materially increased and the grinding action is therefore greater at such a high spot. Even if the high spot should press against the abrasive member 35 enough to move it inward in spite of the resistance afforded by the torque of the shaft 11 in the action of the spring 15 as just pointed out, there would result very little sidewise motion of the shaft 11, if any, because although inward motion of one of the arms 32 is necessarily accompanied by inward motion of the others, such motion is, as has just been pointed out, strongly resisted, and, moreover, the duration of the extra pressure against any one abrasive member is short, and the inertia of the tool is large.

As the grinding action of the abrasive members enlarges the cylinder, the force of the spring 15 tending to move the arms 32 outward, causes the grinding members to

follow the receding cylinder wall until the pin 21 arrives at the end of the rabbet 20. This pin will then prevent further outward motion of the abrasive members. It is therefore possible, by adjusting the length of the path of travel of the pin 21, by means of the screw 24, to determine beforehand the diameter of the re-ground cylinder.

The foregoing discussion of the action of the abrasive members when they meet with a low point or a high point, shows that a very local low point such as a scratch or a scored place, will not cause any sidewise motion of the tool, and the bottom of such a local low point will not be cut at all, unless the cylinder as a whole is enlarged sufficiently to reach to said bottom. It should be borne in mind that the changes in radius mentioned in the preceding discussions are seldom more than one or two hundredths of an inch, and frequently are smaller than this, so that the change in the position of the axis of the cylinder produced by the re-grinding is usually only a few thousandths of an inch. Usually this displacement of the axis is in a direction to change the cylinder spacing of the engine, but as this cylinder spacing is ordinarily several inches, the change in question is proportionately so small that it makes no noticeable change in the character of the engine.

During the grinding action the slots 36 in the abrasive members 35 cause the lubricant which is introduced into the cylinder to flow upward. Between the abrasive members, the lubricant drains downward over the surface of the cylinder and it is again raised by the grooves 36 in the next cutter as the tool rotates. As a result a continual flow of lubricant over the cylinder surface is obtained so that the cut material is rapidly carried away and the surface kept in proper condition for grinding.

If the cylinder is placed on the bed of the drill press or other machine tool on which this instrument is used in a position which is not carefully centered with respect to the shaft 10, the joints 12 enable the shaft 11 to align itself with the axis of the cylinder and the cutters work correctly even though the cylinder is materially out of alignment with the shaft 10. Also the action just described takes place equally well in spite of this offset because the pressure of the cutters against the cylinder depends not upon the torque exerted by the shaft 10 or the alignment with that shaft, but upon the tension in the spring 15. Therefore a truly cylindrical engine cylinder can be made without carefully centering the engine cylinder upon the machine tool. For the same reason it is not necessary to hold the engine cylinder in place upon the machine tool by strapping it down or by any other strong fastening. Ordinarily it is sufficient for the workman

to hold the cylinder in place with his hand. A very great saving in time therefore results, and it is possible to do the work of renewing cylinders with far less skilled workmen than are required by former methods, and the expense of the operation of regrinding cylinders is materially reduced.

I am aware that numerous details of construction may be varied through a wide range without departing from the spirit of this invention, and I therefore do not pur-
10 pose limiting myself further than is necessitated by the prior art.

I claim as my invention:
15 1. In a device of the class described, a carrier, a driving shaft upon which said carrier is rotatably mounted, a barrel rigid with said carrier, a spiral spring, one end of which is attached to said barrel and the
20 other end of which is attached to said shaft, a cover for said barrel rigid with said shaft, means upon the barrel and cover for affording a grasp whereby the cover and barrel may be grasped and moved relative to one
25 another for winding said spring.

2. In a device of the class described, a carrier, a driving shaft upon which said carrier is rotatably mounted, a barrel rigid with said carrier, a spiral spring, one end of
30 which is attached to said barrel and the other end of which is attached to said shaft, a cover for said barrel rigid with said shaft, means upon the barrel and cover for affording a grasp whereby the cover and barrel
35 may be grasped and moved relative to one another for winding said spring, abrading members movably mounted upon said carrier, and means actuated by the rotation of said carrier relative to said shaft for mov-
40 ing said abrading members outward and inward, the inward motion occurring when said spring is wound, whereby the relative motion afforded by said grasping means moves said carriers radially inward to per-
45 mit the introduction of the device into a cylinder.

3. In a device of the class described, a carrier, a plurality of arms pivotally mounted upon said carrier, a cam having straight
50 sides adapted in one position to contact said arms at points distant from said pivots, the motion of the cam towards the last named position being limited by contact of said cam with the pivoted ends of the next neighbor-
55 boring arms.

4. In a device of the class described, a carrier having a plurality of lugs arranged in pairs, each pair extending radially, abrasive carrying arms pivotally mounted one in
60 each pair of said lugs, said arms having circular hub portions surrounding their pivots and side portions tangential to the circular portions, a polygonal cam mounted in said carrier, and adapted in one position to
65 contact the side portions of said arms and

in the other extreme position to contact the circular hub portions of the adjacent arms, spring means tending to move said arms to the position in which their side portions will contact with the sides of the polygonal cam and when the latter is in the last named position will simultaneously move all of said arms against the action of their several springs.

5. In a device of the class described, a carrier having a plurality of lugs arranged in pairs, each pair extending radially, abrasive carrying arms pivotally mounted, one in each pair of said lugs, said arms having circular hub portions surrounding their pivots and side portions tangential to the circular portion, a polygonal cam mounted in said carrier, and adapted in one position to contact the sides of said arms and in the other position to contact the circular hub portions of the adjacent arms, spring means tending to move said arms to the position in which their sides will contact with the sides of the polygonal cam when the latter is in the last named position, whereby rotating the cam away from the last named position will simultaneously move all of said arms against the action of their several springs, and spring means for rotating said polygonal cam in the direction to accomplish said last named motion.

6. In a cylinder grinding machine, a driving shaft, a sleeve member loosely mounted upon said shaft, a yielding connection between said shaft and sleeve, abradant members pivotally mounted upon said sleeve member for swinging movement, a device secured upon said shaft for engagement with said abrasive members to project the same and toward which device said yielding connection urges said members, said shaft having a limited relative rotary movement to said sleeve member, and means for varying such limited relative rotary movement.

7. In a cylinder grinding machine, a driving shaft, a sleeve member connected to said shaft for limited relative rotary movement, an adjustable member carried by said sleeve for varying such relative rotary movement, abradant members hinged to said sleeve member for swinging movement, a driving device on said shaft for engaging said abradant members to project them, and yielding means relatively urging the device and members into projecting relation.

8. In a cylinder grinding machine, a driving shaft, a sleeve loosely mounted upon said shaft, a yielding connection between said sleeve and shaft, a plurality of abradant members hinged to said sleeve, a device upon said shaft for engaging said abradant members to project them, and having relative movement with respect thereto, said yielding connection relatively urging the device and members into projecting relation.

9. In a cylinder grinding machine, a shaft, a sleeve loosely mounted upon said shaft, a yielding connection between said sleeve and shaft, positive means for providing a pre-determined relative rotary movement between said sleeve and shaft, abradant members pivotally mounted upon said sleeve, and a cam device on said shaft for engaging said abradant members to project them, said yielding connection relatively urging the device and members into projecting relation.
10. In a cylinder grinding machine, a shaft, a sleeve member loosely mounted upon said shaft, an adjustable connection between said sleeve member and shaft providing a predetermined relative rotation, abradant members hinged upon said sleeve and a cam device upon said shaft adapted for driving relation with said abradant members, and yielding means relatively urging the device and members into projecting relation.

In testimony whereof I have hereunto subscribed my name.

GEORGE H. BLETTNER.
